UNITED STATES PATENT OFFICE.

JOHN W. LARIMORE, OF SPRINGFIELD, ILLINOIS.

OIL-CAN ATTACHMENT.

994,938.

Specification of Letters Patent. Patented June 13, 1911.

Application filed June 24, 1910. Serial No. 568,749.

To all whom it may concern:

Be it known that I, JOHN W. LARIMORE, a citizen of the United States, residing at Springfield, in the county of Sangamon and 5 State of Illinois, have invented certain new and useful Improvements in Oil-Can Attachments, of which the following is a specification.

This invention relates to an improvement 10 in oil cans or the like.

It is a well known fact that much difficulty is experienced in oiling various machinery such as, for instance, shafting carried by a ceiling. It is found that the ordinary oil can which feeds the oil while in an inverted position, is oftentimes found to be hard to operate on account of obstructions which prevent the said can from being inverted.

20 The principal object of this invention is to provide an oil can by which the egress of oil can be accomplished while the said can is either in an upright or in an inverted position.

25 Another object of the invention is to provide a can of the character described which is extremely simple in construction, easy of operation, and cheap to manufacture.

With these and other objects in view, the 30 invention consists in the construction and novel combination of parts hereinafter fully described, illustrated in the accompanying drawing, and pointed out in the claims here- to appended; it being understood that various changes in the form, proportion, size 35 and minor details of construction, within the scope of the claims, may be resorted to without departing from the spirit or sacrificing any of the advantages of the invention.

40 In the drawing:—Figure 1 is a vertical sectional view of an oil can embodying my invention and showing the said can in an upright position. Fig. 2 is a vertical sectional view showing the can in an inverted position. Fig. 3 is a sectional view of the feed tube on the line 3—3 of Fig. 1.

45 Like reference numerals designate corresponding parts in all the figures of the 50 drawing.

Referring to the drawing, 4 designates an oil can of any suitable design having a bottom 5 and a top 6, said top being provided with an oil inlet 6^a and a central opening 7. A feed tube 8, which is preferably tubular 55 and formed of any suitable metal, is preferably tapered, the upper end 9 being seated within the opening 7 of the top and provided with a peripheral flange 10 which rests upon and is preferably soldered to the 60 top 6 of the oil can, and thereby supports the said feed tube. The lower or larger end 11 of the feed tube extends within the oil can and is spaced from the bottom 5 thereof. A transverse bar 12 is arranged across the 65 lower end 11 of the feed tube and is secured to the said tube by solder or other suitable means. An inclined valve seat 13 is secured within the feed tube above the said cross bar and is preferably formed of a flat metal 70 disk. The said valve seat 13 is provided with a valve opening 14 located near the upper edge thereof, the seat around the said opening being preferably depressed, as shown by reference numeral 15, to form a 75 perfect fitting seat for a ball or gravity valve 16 which is arranged within the tube between the valve seat and the cross bar 12. It will be observed, in this connection, that the cross bar 12 acts as a stop for the said 80 valve and that the said valve constitutes a lower inlet for the oil.

Located near the upper end of the feed tube is an off set casing 17, having an open upper end 18 and a closed lower end 19. 85 This casing is formed integral with the said feed tube. The lower end 19 is downwardly and inwardly inclined toward the feed tube. Formed in the feed tube directly above the said lower end of the casing is an opening 20 90 which communicates with the interior of the casing and the feed tube. An inclined valve seat 21, similar to that in the lower end of the feed tube, is arranged within the casing and preferably above the lower end 19 95 thereof.

A valve opening 22 is formed in the valve seat near the lower end thereof and is preferably depressed as shown by reference numeral 23 to form a perfect seat for the ball 100

or gravity valve 24 which is arranged between the open end 18 of the casing and the said valve seat thereof. A bail or cross bar 25 extends across the said open end of the 5 casing for the purpose of limiting the movement of the said ball valve 24. This valve mechanism constitutes the upper oil inlet for the feed tube.

The upper end of the feed tube is prefer- 10 ably internally threaded, for the purpose of attaching the lower threaded end 26 of a spout 27. Radially projecting from the lower end of the spout above the top of the oil can is a pump chamber 28 having com- 15 munication with the said spout. Arranged within the said chamber is a hand pump 29 of any suitable construction. Check valves 30 and 31 are respectively arranged within the spout above and below the said pump 20 chamber.

From the foregoing, it will be observed that the operation of the can as shown in Fig. 1 will be as follows. In this position the upper inlet is closed and the lower inlet 25 is opened. Upon the operation of the pump 29 oil will be drawn from the oil can, through the said lower inlet and into the feed tube, and thence through the lower check valve 31 into the pump chamber. 30 Upon the instroke of the pump, the oil in the pump chamber will be forced therefrom into the spout 27. This operation can, of course, be repeated until sufficient oil has been forced through the spout.

35 When it is desirous of inverting the oil can, as shown in Fig. 2 of the drawing, the lower inlet will be automatically closed and the upper inlet automatically opened. Upon the operation of the pump, the oil will then 40 flow through the open end 18 of the off set casing, through the valve opening 23, the opening 20 and into the feed tube and thence past the check valve 31 into the pump chamber. Upon the instroke of the pump, 45 the oil will flow from the said pump chamber into the spout. This operation is repeated as often as desired, as before explained.

What I claim is:—

50 1. An oil can including a feed tube, having a valve seat near its lower end, a cross bar extending across the end, a ball valve for the seat movably arranged between the said seat and the cross bar, and an upper inlet for the tube including an oppositely seated gravity valve.

55 2. An oil can including a feed tube, having an off set casing formed near the upper end thereof and comprising an upper inlet, 60 said casing having communication at its upper end with the interior of the can and at its lower end with the interior of the

tube, a gravity valve arranged within the casing, and a lower inlet for the tube including an oppositely seated gravity valve. 65

3. An oil can including a feed tube, having a valve seat near its lower end, a cross bar extending across the end, a ball valve for the seat movably arranged between the seat and the cross bar, an off set casing near 70 the upper end of the feed tube and comprising an upper inlet, said casing having communication at its upper end with the interior of the can and at its lower end with the interior of the tube, and a gravity valve 75 arranged within the said casing.

4. An oil can including a feed tube, having a valve seat near its lower end, a cross bar extending across the end, a ball valve for the seat movably arranged between the 80 said seat and the cross bar, an upper inlet for the tube including an oppositely seated gravity valve, and means for controlling the egress of the oil.

5. An oil can including a feed tube, having an off set casing formed near the upper end thereof and comprising an upper inlet, said casing having communication at its upper end with the interior of the can and at its lower end with the interior of the tube, 90 a gravity valve arranged within the casing, a lower inlet for the tube including an oppositely seated gravity valve, and means for controlling the egress of the oil. 95

6. An oil can including a feed tube, having a valve seat near its lower end, a cross bar extending across the end, a ball valve for the seat movably arranged between the seat and the cross bar, an off set casing near the upper end of the feed tube and comprising an upper inlet, said casing having communication at its upper end with the interior of the can and at its lower end with the interior of the tube, a gravity valve arranged within the said casing, and means for controlling the egress of the oil. 100

7. An oil can having a spout, a feed tube connected with the spout and having a valve seat near its lower end, a cross bar extending across the end, a ball valve for the seat movably arranged between the said seat and the cross bar, an upper inlet for the tube including an oppositely seated gravity valve, and a pump associated with the said spout for controlling the egress of the oil. 110

8. An oil can having a spout, a feed tube connected with the spout and provided with an off set casing arranged near the upper end thereof and comprising an upper inlet, said casing having communication at its upper end with the interior of the can and at its lower end with the interior of the tube, a gravity valve arranged within the casing, a lower inlet for the tube including an op- 120

positely seated gravity valve and a pump associated with the spout for controlling the egress of the oil.

9. An oil can having a spout, a feed tube connected with the spout and provided with upper and lower inlets respectively having oppositely seated gravity valves, a pump chamber radially extending from the spout, check valves respectively arranged within

the spout above and below the pump chamber, and a pump arranged within the said chamber for controlling the egress of the oil. 10

In testimony whereof I hereunto affix my signature in the presence of two witnesses.

JOHN W. LARIMORE.
